PUMP

Leon J. Vetrano, Houston, Tex.

Application April 3, 1936, Serial No. 72,467
Renewed June 19, 1939

2 Claims. (Cl. 103—46)

This invention relates to a pump.

An object of the invention is to provide a pump having a motor adapted to operate the traveling valve of the pump and to be operated by an operating fluid, the operating fluid constituting a part of the pumped liquid which is sent back down into the well under pressure. It is another object of the invention to provide a pump of the character described having upper and lower cylinders and plungers therein, said plungers being connected together and the lower plunger being connected with the traveling valve with an arrangement of passageways whereby high pressure operating fluid will be maintained between the plungers and the pressure of the operating fluid above the upper plunger will be alternately varied whereby the traveling valve of the pump will be operated.

The invention also comprehends a novel type of pilot valve with novel means for actuating the same whereby the pressure of the operating fluid above the upper plunger may be varied.

The invention also includes a novel type of packing element incorporated into the pump and includes means for applying the high pressure operating fluid between the cups of the traveling valve and the surrounding walls of the pump working barrel to exclude deposits of sand, grit and the like.

With the above and other objects in view, the invention has particular relation to certain novel features of construction, operation and arrangement of parts, an example of which is given in this specification and illustrated in the accompanying drawings, wherein:

Figure 1 shows a vertical sectional view of the upper end of the motor.

Figure 2 shows a vertical sectional view of an intermediate portion thereof.

Figure 3 shows a vertical sectional view, showing the lower portion of the motor and the upper portion of the pump proper.

Figure 4 shows a vertical sectional view of the lower end of the pump.

Figure 5 shows a side elevation partly in section of the complete apparatus.

Figure 6 shows a side view partly in section of a packer employed.

Figure 7 shows a transverse sectional view taken on the line 1—1 of Figure 6.

Figure 8 shows a transverse sectional view taken on the line 8—2 of Figure 1.

Figure 9 shows a transverse sectional view taken on the line 9—9 of Figure 1.

Figure 10 shows a transverse sectional view taken on the line 10—10 of Figure 1.

Figure 11 shows a transverse sectional view taken on the line 11—11 of Figure 1.

5 Figure 12 shows a transverse sectional view taken on the line 12—12 of Figure 1.

Figure 13 shows a side view partly in section of a valve cage employed.

Referring now more particularly to the drawings wherein like numerals of reference designate similar parts in each of the figures, the numeral 1 designates the pump tubing which extends to the ground surface and to the lower end of which the motor is connected. The operating fluid will be forced down through said tubing under the required pressure, entering the space 2. There is a valve cage 3 which is attached to the motor body by means of suitable bolts 4 and whose upper end is closed by a plug 5. 15 Attached to the lower end of the motor body 6 is the upper cylinder 7 and attached to the lower end of said upper cylinder 7 there is a lower cylinder 8 having a smaller diameter than the upper cylinder and having a plurality of outlet ports 9 and above said ports also has the gas vent 10. 20 There is an upper piston 11 in the upper cylinder 7 having the downwardly turned cup rings 12 and there is a lower piston 13 in the lower cylinder 8 having the upwardly turned cup rings 14. These 25 pistons are connected by a tubular piston rod 16 which is provided with ports 17 approximately from end to end. An axial tube 18 is attached at its upper end to the lower end of the body 6 and its lower end is extended down into the lower 30 end of the piston rod 16 and is closed by the lower end plate 19. Above said plate the tube 18 has outlet ports 20.

The motor body 6 has an axial bore 21 extending from the lower end thereof upwardly to the 35 valve cage 3 and in this bore there is a pilot valve 22 which will be more specifically hereinafter described.

A pilot valve rod 23 is attached at its upper end to the lower end of the pilot valve 22 and at its 40 lower end extends through the plate 19 and has a flanged nut 24 secured on said extended end and a coil spring 25 is supported on the flange of the nut 24 and surrounds the lower end of the tube 18.

There is also a coil spring 26 which is supported on the lower piston 13 and is confined within the piston rod 16 and its upper end contacts against the flange of the nut 24 when it reaches its upper position. The valve 22 has the upper and lower annular grooves 27, 28, forming 45 seats in which the oppositely arranged balls 29

are engageable to hold the pilot valve in upper or lower position. The balls 29 are urged inwardly by plungers 30 which are seated against the springs 31 and these springs are maintained under compression by the plugs 32 which are 5 screwed into the motor body 8.

The plunger assembly 13 is screwed onto the upper end of the tubular plunger rod 33 which extends downwardly through and beneath the cylinder 8 and attached to its lower end there is the traveling valve 34 of the pump which reciprocates in the pump working barrel 35.

The lower end of the working barrel is controlled by the upwardly opening standing valve 36 of conventional construction. The traveling 15 valve mechanism 34 includes the upwardly opening ball valve 37 and leading downwardly from the lower end of the tubular plunger rod 33 through the wall of the cage of the traveling valve there is a duct 38 which terminates in the opening 39 and through which the high pressure operating fluid may be discharged between the traveling valve and the wall of the working barrel to wash out sand and grit that would otherwise collect therein. The upper end of the pump working barrel 35 is attached to a gland 40 and attached to the lower end of the cylinder 8 there is a gland 41 which has a central downwardly extended sleeve 42 which is secured to the gland 40. Around the sleeve 42 is a bellows 43 which extends from the gland 41 to the gland 40. There is a tube 44 whose upper end is connected with high pressure operating fluid above the plunger 13 and whose lower end is extended into the upper gland 41 and communicates therein with a duct 45 which leads downwardly through the walls of the sleeve 42 and terminates in the bellows 43 as shown in Figure 6.

Surrounding said bellows there is an expandable metal protecting sheath 47 and around this sheath is an expandable packer sleeve 48. Upon the application of high pressure operating fluid through the channel 45 the packer assembly above described will be expanded to form a fluid tight joint with the surrounding well casing 49 so as to separate the column of liquid being pumped from the reservoir in the well beneath.

In operation liquid is pumped down through the tubing 1 and into the space 2 and passes thence through the opening 50 into the cylinder 51 and through the passageway 52 into the space 53 passing thence through the passageway 54 into the passageway 55 through the tube 18. The lower end of this tube 18 opens into the cylinder 7 through the openings 20 and 17 thereby causing pressure to be always on the lower end of the upper piston 11 and against the upper end of the lower piston 13. These pistons, as will be noted, are rigidly connected together by the tubular pumping rod 16 and are rigidly connected to the traveling valve of the pump by the plunger rod 33. As shown in Figures 2 and 3 the pistons 11, 13 are at the limit of the upstroke, and spring 26 has been placed under compression and has forced upwardly the valve rod 23 and valve 22. Said valve 22 has communicated the lower part 56 of the cylinder 51, with the exhaust opening 57, through the passage 52a, thereby relieving the pressure beneath the piston 54a, and said piston has moved downwardly and closed the valve 55a and opened the valve 59 admitting the pressure in the chamber 51 to the passage 60 and thereby to the top of the piston 11. This balances the pressure on both sides of the piston 11. The exhaust pressure on the lower side of

the piston 13 is less than the high pressure on the top of the piston 13 causing both pistons and the pump traveling valve to move downwardly. As the pistons move downwardly the excess liquid beneath the piston 11 is transferred under balanced pressure through ports 17, 20, the tube 18, passageway 54, space 53, channel 52 and valve 59 to passage 60 and thus back to the upper side of piston 11. When these pistons reach the limit of their downward movement the spring 58 will be compressed exerting a downward thrust on the rod 23 and valve 22, unseating the balls 29 permitting the valve 22 to move downwardly until the balls 29 seat in the seat 27 to hold the valve 22 in its lower position and thereby connecting the passage 52a, through the opening 61 with the space 53 which contains operating fluid at high pressure. High pressure fluid is thus on both sides of the piston 54a and there is low pressure above the valve 55a and therefore the valve assembly 54a, 55a, 59, will move upwardly closing the valve 59 and opening the valve 55a. This connects the passage 60 with the space above the piston 11 and with the exhaust channel 62. High pressure liquid is at all times between the pistons 11, 13 and causes said pistons and the pump traveling valve 34 to move upwardly, when the pressure is relieved above piston 11 through exhaust valve 55a, because the area exposed to said pressure of the piston 11 is greater than that of the piston 13. When the pistons reach the limit of their upward movement the cycle will be again completed and ready to begin a new cycle.

The balls 29 and spring pressed plungers 30 maintain the pilot valve 22 in its correct position. Should the power be shut off when the valve 22 is in neutral position, upon return of power, leakage of high pressure liquid will pass from the passageway 52 through the hole 63, connected therewith, into the bore 21 above the pilot valve which in turn balances the pilot valve. The high pressure liquid passes also through the small vent 64 into the cylinder 56 and causes equalization of pressures on both sides of the piston 54 thereby allowing the spring 65 to move the piston 54 upward and so starting the cycle.

The gas vent 10 in the cylinder 8 is located at the lowest limit of downward movement of the piston 13 so that all gas trapped in the cylinder 8 above said vent will be forced out upon downward movement of said piston. The cylinder 8 will be of considerable length and the discharge ports 9 will be located at or near the lower end of said cylinder thereby giving ample space for the pumped liquid between the outlet ports 9 and the gas vent 10. This body of liquid will move up and down with the piston 13 and will act as a shield to prevent the passage of sand or other gritty substances up to the piston 13.

As shown, the pump is at its extreme upstroke; the pilot 22 has just been elevated into position to connect the passageway 52a with the exhaust port 57. This has relieved the pressure in the lower portion 56 of the cylinder 51 and has caused the valve 59 to open and the valve 55 to close. When the valve 59 opened, high pressure liquid was admitted through the opening 50 into the channel 60 and thence to the top of the upper piston 11 thereby balancing the pressure on the top and bottom of the piston 11. On account of the low pressure of the pumped liquid beneath the piston 13, the piston assembly is moved downwardly thereby discharging the pumped liquid in the cylinder 8 out through the outlets 9 into the well casing 49 through which

it passes to the ground surface. Upon such downward movement of the piston assembly the total volume of the cylinders 7 and 8 between the pistons 11 and 13 will be correspondingly decreased and the excess operating fluid between the pistons 11 and 13 will be transferred, into the top of the cylinder 7 above the piston 11 as hereinabove explained to be exhausted upon the next up stroke of the piston assembly; meantime, the traveling valve 34 will have taken in a new charge or load and upon its upward movement this new charge will be elevated and discharged partly through the outlet openings 9 and part of said load will move up on into the cylinder 8 beneath the piston 13. When the piston assembly reaches the limit of its downward movement the pilot valve 22 will be reversed or moved downwardly closing the port 57 connecting the high pressure channel 53 through the ports 61 and the channel 52a with the lower portion 56 of the cylinder 51 thereby causing high pressure liquid to be exerted against the piston 55a to elevate the same and to close the valve 59 and open the valve 55a. The fluid from the top of the piston 11 is thereby exhausted through the channel 60 and the valve 55a into the passageway 62 and thence to the exhaust port 57 whereby the spent operating fluid will be exhausted into the pumped liquid.

The drawings and description disclose what is now considered to be a preferred form of the invention by way of illustration only, while the broad principle of the invention will be defined by the appended claims.

What I claim is:

1. In a pump an upper and a lower cylinder of different cross sectional areas, a piston in each cylinder, means connecting the pistons to move in each direction, as a unit, means for connecting the pistons to the pumping mechanism of the pump, means for applying an operating fluid under high pressure through the upper piston into the cylinders between the pistons and maintaining said pressure, and means for varying the pressure of the operating fluid on one side only of one of the pistons.

2. Pump operating mechanism comprising a pair of cylinders of unequal cross sectional areas, a piston in each cylinder, means to connect the pistons against relative movement whereby the pistons will move as a unit, means for delivering an operating fluid under high pressure through one piston into the space between the pistons, and means for balancing the pressures on opposite sides of the piston of the larger cross sectional area.

LEON J. VETRANO.
